(57) **CLAIM**

The ornamental design for a USB hub, as shown and
described.

DESCRIPTION

FIG. 1 is a front-right-top perspective view of a USB hub
showing our new design;

FIG. 2 is a front-right-bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The uneven-length broken line immediately adjacent to the
shaded area defines the bounds of the claimed design and
forms no part thereof. The even-length broken lines depicting
the remainder of the USB hub form no part of the
claimed design.
